BRASSIÈRE

Sophie M. Curran, Hollywood, Calif., assignor, by
mesne assignments, of one-half to Agnes H.
Dryer, Los Angeles, Calif.

Application August 7, 1948, Serial No. 43,090

4 Claims. (Cl. 2—42)

1

The present invention relates to a brassière and particularly to the type in which a stiff supporting member is used in the brassière between the portion of the breast cups. One of the objects of the present invention is to provide a brassière which may be held firmly in place against the body and support the breasts in their proper position without exerting excessive pressure against them.

In the present invention the supporting structure is so arranged that the brassière is maintained in a position hugging the body. This, in large part, is brought about by a stiff central supporting member and elastic tapes connected to the central member in such positions that they exert but slight pressure against the breasts and what pressure is exerted is in such a direction as to furnish an upward support for the breasts themselves which are not only cushioned by the extensibility of the elastic tapes but in addition the pull on the shoulder straps is relieved. The fabric of the brassière itself is so formed that the breasts may rest in the breast cups in a free position, the size of the cups being such, of course, to provide the proper fit, so that excessive looseness is avoided.

The combination of structural features embodied in the brassière of the present invention are such as to provide great wearing comfort permitting the individual perfect freedom of motion without the least discomfort. Other merits and advantages of the present invention will more readily be understood from a consideration of the specification below when taken in connection with the drawing illustrating an embodiment of the invention in which:

Figure 1 shows in elevation the brassière embodying the present invention.

Figure 2 shows an enlarged fractional view of a portion of the brassière shown in Figure 1.

Figure 3 shows an enlarged sectional view taken on a line 3—3 of Figure 1.

In the drawings the brassière, as shown, may be made of woven silk, rayon, or satin material and is usually fairly durable in character as far as cloth is concerned and yet thin, flexible and soft against the body. The fabric or cloth 1, forming the brassière itself is seamed and reinforced by tapes 2 and 3 extending slightly diagonally up and down and is further provided with gussets 4 and 5 and tucks 5' to form the breast pockets 6 and 7. These breast pockets are supported at their inner side edges by a stiff or rigid U-shaped member 8, the side prongs 9 and 10 of which extend upward into the tubes or

2

sleeves 11 and 12, respectively, which are at the side edges of the breast pockets. These prongs extend substantially only straight upwards along the inside edges of the breast pockets and not over the top so that no pressure is exerted over the position of the breast but, on the other hand, the prongs act merely as a central support and a support for the inner side edge of the breast pocket. These upwardly extending sleeves are covered on the inside by a soft felted fabric 14, and the U-shaped stiffening member is also covered by a similar fabric. The lower bend of the U has attached to it a fabric member 15 covered by the soft felted material, which fabric 15 extends downward as a tab and is provided on the inside with snap fasteners 16 which snap to corresponding elements 16' sewed to the brassière fabric. The whole front section of the sleeves, the stiffening, U-shaped member and the covered tab, are, therefore, all provided with a soft material which rests easily and without any discomfort against an individual at the position of the breastbone and not against the fleshy part of the breast. Attached between the sleeves and the brassière fabric and extending away in opposite directions from the prongs of the U are two elastic tapes, an upper tape 17 and a lower tape, 18. The upper tape 17 is attached in the vicinity of the upper end of the stiffening member which may be of metal or other material and extends downward diagonally to join the lower member 18 which is attached between the sleeve and the fabric of the brassière just above the bend in the U-shaped member. These two elastic tapes joining one another substantially in the position of the first gusset 4, near the lower edge of the brassière and thereafter extend in a single tape 19 to the end of the back of the brassière as at 20 and 21 where they are attached at the bottom edge. An elastic section 22, may be inserted on one or both sides of the brassière between the position of the end of the tape 19, and the fastening edges 23 and 24. The insertion of the elastic section 22 before the fastening edges effectively extends the length of the elastic strap and also avoids the double elastic tension which would be present if the elastic strap 19 were connected to the further edge of the elastic section 22.

50 The brassière is also provided with the usual shoulder straps 25, which may be adjusted over the shoulders in the usual manner.

It will be noted in the construction of the present invention that the U-shaped member extends only vertically upward at the center and therefore

rests in position against the breastbone in the average person. The strap 17 slopes diagonally downward quite steeply and joins the strap 18 at the bottom of the brassière. In this way the section 17 of the elastic strap provides a yielding support under the breast while the horizontal section tends to draw the lower part of the brassière against the ribs holding the top of the prongs in position against the body and making the elastic tape 17 a true extensible cradle from its topmost support at the top of the prong to its attachment at the junction of the sections 18 and 19, which rest firmly against the body, where the ribs are positioned. The brassière is firmly positioned lightly suspended from the shoulders and will not readily move out of place. The inner upright supporting edge of the breast cup and the lower edge, are, therefore, held in position regardless of the movement of the individual and these two elements, together with the top shoulder strap, securely positions the breasts without exerting any special tension against them.

As will be noted from Figure 3 the central section 30 of the brassière is re-inforced by a double fabric and over-stitched re-inforcing tapes 31 and 32, the latter of which extend over the base of the U and under the wings 33 of the sleeve cover.

Having now described my invention, I claim:

1. A brassière of the type described comprising flexible fabric material forming a band around the bust having ends adapted to be fastened together at the back of the individual, said brassière having a pair of breast cups formed therein, the inner side edges of the breast cups terminating in vertically extending sleeves spaced from one another and having open lower ends positioned just above the lower margin of the central region of the brassière, a stiff U-shaped member having its prongs fitting closely in said sleeves and its cross member secured in the lower margin of said central region and two pairs of elastic, yielding, flexible strap members, one strap member of each pair attached to each sleeve at each side near the bend of the U adjacent the top of the lower margin of said band and the other strap member of each pair attached to each sleeve at each side near the top of the prongs, the strap members forming a pair joining each other adjacent the inner lower region of the breast cup with the strap members from the bend of the U extending along each side to the ends of the brassière at the lower portion thereof.

2. A brassière of the type described, comprising flexible fabric material forming a band around the bust having ends adapted to be fastened together at the back of the individual, said brassière having a pair of breast cups formed therein, the inner side edges of the breast cups terminating in vertically extending sleeves spaced from one another and having open lower ends positioned just above the lower margin of the central region of the brassière, a stiff U-shaped member having its prongs fitting closely in said sleeves and its cross member secured in the lower margin of said central region, said cross member having a flap on the bottom of the U with snap fasteners attaching the member to the brassière along its lower margin in the central section, and two pairs of elastic, yielding, flexible strap members, one strap member of each pair attached to each sleeve at each side near the bend of the U adjacent the top of the lower margin of said band

and the other strap member of each pair attached to each sleeve at each side near the top of the prongs, the strap members forming a pair joining each other adjacent the lower region of the breast cup with the strap members from the bend of the U extending along each side to the ends of the brassière at the lower portion thereof.

3. A brassière of the type described comprising a flexible fabric material forming a band around the bust having ends adapted to be fastened at the back of the individual, the brassière having a narrow section at a position corresponding to a narrow region between the breasts of the individual, a pair of breast cups formed in the brassière at each side of the narrow section having a vertically extending sleeve formed in the margin at each side of the narrow section, a U-shaped stiffening member having its cross member attached to the brassière at said narrow section and the prongs thereof fitting into said sleeves, and two pairs of elastic, yielding, flexible, strap members, one strap member of each pair attached to each sleeve at each side near the bend of the U adjacent the top of the lower margin of said band and the other strap member of each pair attached to each sleeve at each side near the top of the prongs, the strap member forming a pair joining each other adjacent the lower region of the breast cup with the strap members from the bend of the U extending along each side to the ends of the brassière at the lower portion thereof.

4. A brassière of the type described comprising a flexible fabric material forming a band around the bust having ends adapted to be fastened at the back of the individual, the brassière having a narrow section at a position corresponding to a narrow region between the breasts of the individual, a pair of breast cups formed in the brassière at each side of the narrow section having a vertically extending sleeve formed in the margin at each side of the narrow section, a U-shaped stiffening member having its cross member attached to the brassière at said narrow section and the prongs thereof fitting into said sleeves, and two pairs of elastic, yielding, flexible, strap members, one strap member of each pair attached to each sleeve at each side near the bend of the U adjacent the top of the lower margin of said band and the other strap member of each pair attached to each sleeve at each side near the top of the prongs, the strap members forming a pair joining each other adjacent the lower region of the breast cup with the strap members from the bend of the U extending along each side to the ends of the brassière at the lower portion thereof, said band having an elastic section in a position adjacent the end of the brassière and said elastic strap member extending to said elastic section.
